UNITED STATES PATENT OFFICE.

FRANCIS J. COLE, OF SCHENECTADY, NEW YORK.

LOCOMOTIVE-ENGINE.

1,024,620.

Specification of Letters Patent. Patented Apr. 30, 1912.

Application filed December 20, 1911. Serial No. 666,903.

To all whom it may concern:

Be it known that I, FRANCIS J. COLE, of Schenectady, in the county of Schenectady and State of New York, have invented a 5 certain new and useful Improvement in Locomotive-Engines, of which improvement the following is a specification.

My invention relates to means for elastically supporting the frame and connected 10 members of a locomotive engine, on the driving axles thereof, and its object is to provide a construction wherein the area of bearing surfaces on the axles may be increased to a material extent above that which has been 15 obtainable in ordinary practice, and the application of weight to the journals of the driving boxes shall be effected uniformly throughout their length, without reduction of the maximum permissible distance over 20 frames, thereby minimizing the lost motion and wear of journals and driving boxes due to the action of the horizontal forces developed in the operation of the locomotive.

To this end, my invention, generally 25 stated, consists in the combination, with a locomotive frame of bar type, of pedestal jaws which are inwardly extended to provide increased bearing surface, a driving box fitting a driving axle journal between 30 said pedestal jaws, a spring transferring weight borne by the frame to said driving box, and means for effecting the application of weight from the spring to the driving box, uniformly throughout the length 35 thereof.

The improvement claimed is hereinafter fully set forth.

The design of locomotive driving boxes, as 40 ordinarily exemplified in practice, has contemplated only provision for the weight which they were required to support, so that their sizes have been in direct proportion to the load borne by the driving wheel journals on which they were applied. To this extent 45 they have been satisfactory, so far as the mere support of weight is concerned, but have failed to be so as to their resistance to horizontal forces acting upon them, with the result of being subject to undue and excessive wear. This is particularly the case as to 50 the exceptionally large locomotives which have been recently adopted to a considerable and increasing extent, as in these, on account of their dimensions, it has been necessary to 55 increase the transverse spacing between cen-

ters of cylinders, while at the same time, the distances apart of frame centers has been actually decreased, by reason of the requirement of increase of length of axle bearings and maintenance of central location of 60 frames relatively to the driving axle boxes.

The standard gage of 4 feet 8 $\frac{1}{2}$ inches in the United States, imposes certain positive limitations on the construction of locomotives, among which are the transverse distance between driving wheel hubs, which probably does not exceed about 55 inches at 65 the present time. In order to provide driving boxes of increased length, in recent high powered locomotives, it has been necessary 70 to correspondingly decrease the distance between the centers of the side members of the frame, and this decrease, in connection with the equally necessary increase in the distance between cylinder centers, has caused 75 the horizontal forces acting on the frame and driving axles and boxes to increase in greater proportion than the load borne on the journals, so that while the vertical pressure per square inch of bearing surface, due to 80 weight on journals, has been maintained at a fairly constant figure by the increase of diameter and length of the driving boxes, yet the bearing pressure due to the horizontal forces has increased in materially greater proportion, with the result that the pressures per 85 square inch due to said horizontal forces have induced excessive wear on the driving boxes, and the rapid accumulation of lost motion, the knocking and pounding caused 90 thereby requiring renewal of the driving box bearings after a mileage service which is much less than that previously obtainable.

In order that the wear of the driving boxes shall be uniform, and that of the journals cylindrical and not conical, it is absolutely requisite that both the vertical and the horizontal forces shall, in the present standard constructions, be applied centrally 95 in the length of the bearings, and, consequently, that the side frame members shall be spaced transversely so that their central planes shall coincide with the middle transverse planes of the driving boxes. Such spacing of the frame members, however, involves the objection of largely increasing 100 the pressures due to the horizontal forces acting on the driving boxes. The normal piston thrust is largely increased by the greater leverage ratio resultant upon the 105 110

narrow frame centers and wide cylinder centers, this ratio being, roughly stated, about two to one, and this force is further increased, at certain positions of the cranks, 5 by the reaction of the cranks on opposite sides.

My improvement is designed to provide a construction, which, while conforming with the structural requirements of large locomotives above stated, shall be exempt from the resultant objections obtaining in prior practice, by admitting of the application of driving boxes of maximum obtainable length, in connection with frames of maximum transverse spacing, without involving the increase, above noted, in the horizontal forces acting on the driving boxes and driving axle journals.

In the accompanying drawings: Figure 20 1 is a plan or top view of a portion of a locomotive engine frame and accessory members thereof, illustrating an application of my invention; Fig. 2, a vertical longitudinal section, taken in the central plane of the locomotive; Fig. 3, a vertical transverse section, in the central plane of the driving axle; Fig. 4, a horizontal central section, in the same plane; Fig. 5, a section, similar to Fig. 3, illustrating a modification of 25 structural detail; Fig. 6, a transverse section, on an enlarged scale, through the spring seat, on the line *a a* of Fig. 5; Fig. 7, a section similar to Fig. 3 and Fig. 5, illustrating a further structural modification; Fig. 8, a transverse section, on an enlarged 30 scale, through the spring seat of Fig. 7, on the line *b b* thereof; Fig. 9, a plan or top view, illustrating a further structural modification; Fig. 10, a vertical longitudinal section 35 of the same, taken on the line *c c* of Fig. 11; Fig. 11, a vertical transverse section, in the central plane of the driving axle; and, Fig. 12, a similar section, on the line *d d* of Fig. 10.

My invention is herein exemplified as applied in a locomotive engine, the frame of which is of the standard "bar" type, and comprises two side members which are, as in present practice, spaced at the maximum 40 distance apart available under the necessary limitation imposed by the width between driving wheel hubs. Each of the side frame members, comprises, so far as the portion thereof in which the driving 45 axles are fitted is concerned, the usual top rail, 1, bottom rail, 2, and connecting vertical pedestals, each of which consists of a pair of pedestal jaws, 3, in which a driving box, 4, is fitted between a wedge, 4^a, and a shoe, 4^b, in the usual manner. The driving box is provided with a bearing, 4^c, for one 50 of the journals, 6^a, of a driving axle, 6, upon which are secured a pair of driving wheels, 7, and with a lubricant cellar, 4^d, located 55 below the journal. The open space between

the sections of the lower rail, at the bottom of the pedestal, is spanned by a pedestal tie, 5, secured removably in position by bolts, 5^a.

Referring first to Figs. 1 to 4 inclusive, in the practice of my invention, the driving boxes, 4, and driving axle journals, 6^a, are made of materially increased length, as compared with the ordinary present practice, and the bearing surfaces thereof on the frame members are correspondingly increased by inward extensions of the pedestals, provided in and by supplemental or auxiliary pedestal jaws, 8, which are fixed to the main pedestal jaws, 3, with their inner faces in line with those of the main pedestal jaws, so as to present continuous plane surfaces for contact with those of the outer surfaces of the wedges and shoes. The supplemental pedestal jaws may, in some cases, be made integral with the main pedestal jaws, but are preferably, as shown, separate therefrom and firmly connected thereto, as by bolts, 8^a. The pedestal jaws of the opposite side frame members, at each side of the driving axle journals, are also preferably 60 connected one to the other by transverse webs or braces, 8^b, by which their strength and rigidity are materially increased, and which additionally serve to perform the important function of transverse braces for 65 the frame. The braces, 8^b, are herein shown as integral with the supplemental pedestal jaws, but may, if preferred, be made separate therefrom and suitably secured thereto, and they are also preferably connected at top and bottom by plates or bars, 8^c, extending adjacent to and parallel with the side members of the frame. It will also be 70 obvious that the extensions of the four pedestal jaws of a driving axle, together with the pedestal ties thereof, the equivalent of the lower braces, 8^c, shown in the drawings, may, if desired, be made in an integral U-shaped casting.

It is desirable, for structural reasons, that 75 the spring rigging, through which that portion of the weight of the frame and members of the locomotive connected thereto which is borne by the driving axles is transmitted to the latter, should retain its normal position, *i. e.*, in line centrally with the side frame members. It is also absolutely requisite, in order to prevent one sided action and irregular wear, that the vertical forces acting through the spring rigging 80 should be applied uniformly to the driving boxes throughout their length, that is to say, either midway of their ends or at points equally distant therefrom. In order 85 to comply with these conditions, the weight acting on the springs, 9, which may, as shown, remain in line centrally with the vertical central planes of the side frame members, is transmitted from the springs to the driving boxes through transversely 90

extending spring saddles, 10, on the tops of which the spring bands, 9, are supported, and from which the weight is applied to the driving boxes through downwardly projecting spring bearings, 10^a, each of which abuts on the adjacent driving box, 4, in a plane located midway between the ends thereof.

It follows, from the construction above described, that the weight borne by each of the driving boxes is applied to and acts thereon uniformly throughout its length. The spring seat, 10, is, in this instance, shown as extending integrally from the spring of one of the driving boxes of an axle to the spring of the other, and, also, as having the spring bearings, 10^a, formed integral with it. Such specific construction is not, however, of the essence of my invention, as independent spring seats, may, as hereinafter specified, be provided, and the spring bearings, 10^a, may be formed separately from the spring seat, and may be duplicated for each spring, so as to apply the weight to the driving boxes in two parallel planes, located at substantially equal distances from their ends.

Figs. 5 to 8 inclusive illustrate a modification of structural detail, embodying the same essential operative features as the embodiment of the invention first described, and varying therefrom only as to the specific form of the spring saddle and spring bearings. As shown in Figs. 5 and 6, the spring bearings, 10^a, are formed separately from the spring seat, 10, and are detachably secured thereto by bolts, 10^b, said bearings abutting on the driving boxes midway of their length, as in the instance first described. Figs. 7 and 8 show the spring seat as a composite three part structure, comprising two independent end seat sections proper, 10, 10, on which the spring bands rest, each of said sections having a downwardly extending spring bearing, 10^a, which abuts on the driving box above which it is located, adjacent to the outer end thereof. Each of the seat sections abut, at its inner end, on the adjacent end of a transversely extending connecting section, 10^c, having supplemental spring bearings, 10^d, extending downwardly from its lower side and abutting on the adjacent driving boxes at substantially the same distance from their inner ends as the spring bearings, 10^a, of the seat sections, 10, are spaced from their outer ends. The weight transmitted to the driving boxes through the springs, 9, is thus applied to the driving boxes uniformly throughout their length.

In the further modification illustrated in Figs. 9 to 12 inclusive, the springs, 9, of each driving axle are spaced more closely together than in the instances previously described, their longitudinal central planes

being located at a less distance apart than those of the side frame members, and each spring is supported on a spring seat, 10, having two downwardly extending spring bearings, 10^a, which abut on the driving box 76 above which the spring seat is located, at substantially equal distances from its ends. The spring hangers, 9^b, at each end of the springs of the driving boxes of each axle, are coupled one to the other by a transverse 75 connecting bar, or a pair of connecting bars, 11, to which they are pivoted by pins, 11^a, and said connecting bar is coupled by pins, 11^b, to lower spring hangers, 9^c, the lower ends of which are coupled to equalizers, 9^d, 80 or to the frame rails, as the driving wheel arrangement may require. The independent spring seats, 10, of the opposite driving boxes, are thereby connected for the transmission of strain from one side frame member 85 to the other, as in the instances before described.

It will be obvious that various structural modifications, embodying the spirit and operative principle of my invention, may be 90 made by the skilled constructor, without departure therefrom, and I do not therefore limit my invention to the specific structural embodiments herein set forth.

I claim as my invention, and desire to secure by Letters Patent:—

1. The combination, with a locomotive frame of bar type, of pedestal jaws which are inwardly extended to provide increased driving box bearing surface, and a driving 100 box fitting a driving axle between said pedestal jaws.

2. The combination, with the two side frame members of a locomotive frame of bar type, of opposite pairs of inward pedestal jaw extensions, which provide increased driving box bearing surface, transverse connections securing each of the pedestal jaw extensions of one side frame member to the opposite pedestal jaw extension of the 110 other, and driving boxes fitting a driving axle between the frame pedestal jaws and the adjoining faces of the pedestal jaw extensions.

3. The combination, with a locomotive 115 frame of bar type, of opposite pairs of inwardly extended pedestal jaws, driving boxes fitting, independently one of the other, in said pairs of pedestal jaws, springs whose longitudinal central planes 120 are spaced at a greater distance apart than the middle planes of the driving boxes, and means for applying weight borne by the springs to the driving boxes, at substantially equal distances from their ends. 125

4. The combination, with a locomotive frame of bar type, of opposite pairs of inwardly extended pedestal jaws, transverse connections securing each of the extended pedestal jaws of one side frame member to 130

- the opposite extended pedestal jaw of the other, driving boxes fitting, independently one of the other, in said pairs of pedestal jaws, springs whose longitudinal central planes are spaced at a greater distance apart than the middle planes of the driving boxes, and means for applying weight borne by the springs to the driving boxes, at substantially equal distances from their ends.
5. The combination with the two side members of a locomotive frame of bar type, of a U shaped member having a pair of pedestal jaw extensions at each of its ends, the inner faces of which extensions aline with those of the pedestal jaws of a side frame, to provide increased driving box bearing surface, connections securing said U shaped member to the side frame members, driving boxes fitting, independently one of the other, in the frame pedestal jaws and extensions, springs whose longitudinal central planes are spaced at a greater distance apart than the middle planes of the driving boxes, and means for applying weight borne by the springs to the driving boxes, at substantially equal distances from their ends.
6. The combination, with a locomotive frame of bar type, of opposite pairs of inwardly extended pedestal jaws, driving boxes fitting, independently one of the other, in said pairs of pedestal jaws, springs whose longitudinal central planes are spaced at a greater distance apart than the middle planes of the driving boxes, means for applying weight borne by the springs to the driving boxes at substantially equal distances from their ends, and means for transmitting the application of weight between said driving boxes.
7. The combination, with a locomotive frame of bar type, of a pair of pedestal jaws which are inwardly extended to provide increased bearing surface, a driving box fitting a driving axle journal between said pedestal jaws, a spring whose longitudinal central plane is located on the outer side of the middle plane of the driving box, and means for effecting the application of weight from the spring to the driving box, uniformly throughout the length thereof.
8. The combination, with a locomotive frame of bar type, of a pair of pedestal jaws which are inwardly extended to provide increased bearing surface, a driving box fitting a driving axle journal between said pedestal jaws, a spring whose longitudinal central plane is located on the outer side of the middle plane of the driving box, and a spring seat interposed between said
- spring and driving box and applying weight to the latter uniformly throughout its length.
9. The combination, with a locomotive frame of bar type, of a pair of pedestal jaws which are inwardly extended to provide increased bearing surface, a driving box fitting a driving axle journal between said pedestal jaws, a spring whose longitudinal central plane is located on the outer side of the middle plane of the driving box, a spring seat supporting said spring, and spring bearing means interposed between said spring seat and driving box and applying the weight borne by the spring to the driving box, at substantially equal distances from its ends.
10. The combination, with a locomotive frame of bar type, of pedestal jaws which are inwardly extended to provide increased bearing surface, a driving box fitting a driving axle journal between said pedestal jaws, a spring transferring weight borne by the frame to said driving box, a spring seat supporting said spring, and spring bearing means interposed between said spring seat and driving box and effecting the divided application of the weight borne by the spring to the driving box uniformly throughout its length, in planes at substantially equal distances from its ends.
11. The combination, with the two side members of a locomotive frame of bar type, of pairs of pedestal jaws which are inwardly extended to provide increased bearing surface, driving boxes fitting driving axle journals between said pedestal jaws, springs whose longitudinal central planes are spaced at a greater distance apart than the middle planes of the driving boxes, spring seat members interposed between said springs and driving boxes and applying weight to the latter uniformly throughout their length, and means connecting the spring seat members of the opposite driving boxes.
12. The combination, with the two side members of a locomotive frame of bar type, of pairs of inwardly extended pedestal jaws, transverse connections securing each of the pedestal jaws of one side frame member to the opposite pedestal jaw of the other, and longitudinal connections securing the transverse connections one to the other, adjacent to the side frame members.

FRANCIS J. COLE.
